UNITED STATES PATENT OFFICE.

JONATHAN N. HOLEM, OF PLYMOUTH, INDIANA.

CHURN.

SPECIFICATION forming part of Letters Patent No. 269,207, dated December 19, 1882.

Application filed March 10, 1882. (No model.)

To all whom it may concern:

Be it known that I, JONATHAN N. HOLEM, a citizen of the United States of America, residing at Plymouth, in the county of Marshall 5 and State of Indiana, have invented certain new and useful Improvements in Churns, of which the following is a specification.

This invention relates to rotary churning; and it consists in the construction and arrangement 10 of parts, as hereinafter more fully described and claimed.

In the annexed drawings, illustrating the invention, Figure 1 is a side elevation with part of the outside casing cut away. Fig. 2 is 15 a sectional view taken on the line *x x* of Fig. 3, as indicated by the arrow. Fig. 3 is a top view with the cover removed.

Similar letters of reference refer to similar parts throughout the several views.

20 A is the outside or casing of the churn. It is cylindrical in its shape and divided into two parts—the bottom or lower part, B, and top or cover C—so arranged that the two parts may be readily attached securely together and 25 separated at the pleasure of the operator or other person. B and C are provided with bearings *b b*, in which the journals *c c* on the end of shaft D revolve.

D is a horizontal shaft having journals *c c*, 30 and revolving in bearings *b b*, one end of the shaft being extended beyond the outside of the casing A for the reception of the operating crank-handle E, which is readily attached to the shaft D. Upon said shaft D, securely 35 attached to the same and revolving therewith, are two beveled-gear wheels, the diameter of one being greater than the other, the larger wheel being designated by the letter F and the smaller by G. F meshes in the beveled gear H on top of plate K and G meshes in the beveled-gear wheel *l* on the end of the vertical 40 revolving shaft L.

M is a cross-bar on the inside of the casing A, near the top of B, which rests firmly in 45 the slots *d d*, or equivalent, and at the same time removable for the purposes of withdrawing the several inside parts for cleaning or for any other cause. M has a bearing, *e*, for the top journal of the vertical shaft L. The shaft 50 L passes through plate K and cross-pieces *ff* of large dasher-frame R, and is journaled at

its lower end in bearing on bottom of casing B. The shaft L revolves independent of the plate K and frame-dasher R. It carries the square dasher S, composed of the upright pieces 55 *m m* and cross-pieces *n n*, the cross-pieces *n n* being secured to the vertical shaft L, so that the dasher-frame S will revolve with the shaft L and on the inside of the square frame R, and revolving independent therefrom.

R is a square dasher-frame composed of the cross-pieces *f f* and vertical pieces *g g*. R is secured to the bottom of the circular plate K in any appropriate manner and revolving therewith.

K is a plate on the top of R, and having on its top surface the circular beveled gear H, securely fastened to the same. The plate K fits against the inside of the casing, yet left free to revolve therein. It is provided with a rubber washer, *t*, underneath to prevent the contents of the churn splashing up over the plate while being operated. This washer *t* may be attached to the inside of the casing A instead of the plate K.

If desired, the casing A may be provided with a glass window for the purpose of watching the operation within.

The several parts may be made of any suitable material such as churning are usually made 80 of, and for the purposes desired.

The manner of operation is as follows: Upon turning the crank-handle E in either direction the shaft D will revolve, carrying with it the bevel-gear F and G. F, meshing in the bevel-gear H on the top of plate K, will revolve the dasher R in one direction, and the bevel-gear G, meshing in the bevel-wheel *l*, will revolve the shaft L, thereby revolving the dasher S in the opposite direction from that in which R moves, the velocity of R and S being such as desired by gearing of size to suit the velocity required when turning the crank in one direction. By reversing it the direction of the movement of the dasher R and S will be reversed, thereby securing what I call a "double reversible" action. With most of the churning now in use the cream is turned in one way, while my double reversible action reverses the cream and whips the butter out. All of 90 the several parts are easily removed for cleaning, the machinery being very simple.

Having described my invention, what I claim as new, and desire to secure by Letters Patent, is—

1. In a churn, the rubber washer *t*, in combination with the plate *K* and the casing *A*, substantially as shown and described, and for the purpose specified.

2. The combination, in a churn, of the casing *A*, composed of parts *B* and *C*, provided with bearings *b b*, with the revolving shaft *D*, provided with journals *c c*, beveled gear *F* and *G*, cross-bar *M*, slots *d d*, vertical shaft *L*, hav-

ing beveled gear *l*, and dasher-frame *S*, the dasher-frame *R*, the revolving plate *K*, having beveled gear *H*, and rubber washer *t*, all as arranged and operating substantially as described and shown, and for the purpose set forth.

In testimony whereof I affix my signature in presence of two witnesses.

JONATHAN N. HOLEM.
